J. C. JENSEN.
BABY FEEDER AND TOY HOLDER.
APPLICATION FILED JULY 28, 1913.

1,097,097.

Patented May 19, 1914.

UNITED STATES PATENT OFFICE.

JENS C. JENSEN, OF FRESNO, CALIFORNIA.

BABY-FEEDER AND TOY-HOLDER.

1,097,097.

Specification of Letters Patent. Patented May 19, 1914.

Application filed July 28, 1913. Serial No. 781,649.

To all whom it may concern:

Be it known that J. JENS C. JENSEN, a citizen of the United States, residing at Fresno, in the county of Fresno, State of California, have invented certain new and useful Improvements in Baby-Feeders and Toy-Holders; and I do hereby declare the following to be a full, clear, and exact description of the invention, such as will enable others skilled in the art to which it appertains to make and use the same.

This invention relates to combined baby feeders and toy holders and has for an object to provide an extremely simple bracket 15 and milk bottle cover that will have novel means for supporting the bottle at various adjusted angular positions from the horizontal whereby the bottle may be freely held by the lips of the infant whether the latter is 20 reclining or in a sitting up position.

A still further object of the invention is to provide a bracket having means for preventing the bottle swaying laterally but permitting of the bottle swaying longitudinally and at the same time yielding vertically.

A still further object is to provide a device of this character to which a toy may be secured after the infant is through feeding.

With the above objects in view the invention consists of certain novel details of construction and combination of parts herein-after fully described and claimed, it being understood that various modifications may be made in the minor details of construction within the scope of the appended claims.

In the accompanying drawing illustrating this invention:—Figure 1 is a side elevation showing the device embodying my 40 improvements. Fig. 2 is a plan view. Fig. 3 is a front elevation. Fig. 4 cross sectional view on the line 4—4 Fig. 1.

Referring now to the drawing in which like characters of reference designate similar parts, 10 designates a rod which is slidably fitted in a ball clamp 11 that may be attached to the baby carriage or the crib, the rod being forked at the free end and the branches 12 being terminally equipped with 45 hooks 13 to which are secured helical springs 14, these springs converging toward their lower ends and being connected to a swivel snap hook 15.

The milk bottle 16 is equipped with a 50 cloth cover 17 which buttons snugly upon

the bottle as shown at 18 and is provided on one side with a substantially semi-circular handle 19 that may be formed of a link chain or strap and in the present embodiment is illustrated as a strap that is fixed at 60 the ends or otherwise secured to the cover and is provided with a series of perforations 20 in any one of which the snap hook may be engaged whereby to vary the angle of the bottle from the horizontal. The 65 branched end of the rod will prevent the bottle from swinging laterally but will permit of the bottle swinging backwardly and forwardly between these branches, while the springs 14 will permit of the bottle yielding 70 vertically a slight distance. The above described device may be adjusted on the ball bracket while the bottle may also be adjusted angularly relatively to the horizontal so that the nipple 21 will rest lightly between 75 the lips of the child and thus be held without effort. After the infant is through feeding the bottle may be detached by disengaging the handle of the cover from the snap hook and a toy substituted for the infant's 80 amusement.

The cover of the bottle serves a two-fold purpose, namely it keeps the milk warm and at the same time holds the bottle in position relatively to the infant so that the 85 latter can comfortably feed.

From the above description it will be seen that I have provided an extremely simple and inexpensive device of the character described which is formed of a few parts that 90 are inexpensive in construction and will not easily get out of order.

What is claimed, is:—

1. The combination of an attaching bracket including a rod having a forked 95 end, a pair of springs depending from the branches of the forked end, a snap hook connecting the lower ends of said springs, a milk bottle having a nipple, and a cover removably secured on said bottle and provided with a lateral handle having a longitudinal series of openings in which said snap hook is arranged to be interchangeably engaged.

2. The combination of an attaching bracket including a rod having a forked end, a pair of springs depending from and converging from the branches of said forked end, a snap hook connecting said springs, a milk bottle having a nipple, a fabric cover 105 110

buttoned tightly upon the milk bottle, and
an outwardly projecting handle on said
cover having a longitudinal series of open-
ings in which said snap hook is arranged to
5 be interchangeably engaged whereby said
bottle may be turned with respect to the
horizontal.

In testimony whereof, I affix my signa-
ture, in the presence of two witnesses.

JENS C. JENSEN.
